UNITED STATES PATENT OFFICE.

DAVID M. MOTHERWELL, OF CHICAGO, ILLINOIS, ASSIGNOR TO THE WHITMAN & BARNES MANUFACTURING CO., OF AKRON, OHIO, A CORPORATION OF OHIO.

KNOCKER FOR TRAVELING CARRIERS.

SPECIFICATION forming part of Letters Patent No. 767,652, dated August 16, 1904.

Application filed August 6, 1903. Serial No. 168,494. (No model.)

To all whom it may concern:

Be it known that I, DAVID M. MOTHERWELL, a citizen of the United States, residing at Chicago, Cook county, Illinois, have invented a new and useful Improvement in Knockers for Traveling Carriers, of which the following is a specification.

My invention relates to stops or knockers for traveling carriers, and is especially adapted for use with carriers which operate to raise a load vertically, convey it horizontally along a horizontally-suspended rope or cable, and release it at a desired point beneath the rope or cable.

15 The object of my invention is to provide a stop or knocker which may be coupled over the rope or cable (without the necessity of taking down the latter) and locked thereon against longitudinal movement, while left free

20 to swing from side to side thereon, thereby contacting properly with the releasing mechanism of the carrier in the different positions which the carriers and stops are likely to assume when the rope is kinked or turned.

25 A further object is to provide a stop or knocker which may be readily removed from the cable or shifted from point to point thereon without taking down or otherwise disturbing the cable.

30 In the drawings, Figure 1 is a side view of a stop embodying my invention adapted to operate the releasing mechanism of the traveling carrier shown. Fig. 2 is a top view of the frame of the carrier on line 2 of Fig. 1.

35 Fig. 3 is a central longitudinal section of the stop and carrier. Fig. 4 is a sectional view on line 4 of Fig. 3. Fig. 5 is a view on line 6 of Fig. 1 looking in the direction of the arrow. Fig. 6 is a similar view on line 7 of Fig. 1.

40 A indicates any suitable carrier adapted to operate with the stop E. It consists, preferably, of the two parts 8 and 9, fastened together by bolts or rivets 10, 11, 12, 13, 14, and 15, the bolts 14 and 15 being the axes about which the

45 flanged wheels 16 and 17 turn. The bolts 12 and 13 support the flanged pulleys 18 and 19, while the bolts 10 and 11 support the detents 20 and 21. The frame and wheels may be of

any suitable construction adapted to travel upon the track or cable and support the pulleys and detents. 50

B indicates the track or cable, adapted to be stretched between points of support and to afford a rail-support and guide for wheels 16 and 17. It is usually constructed of steel or 55 iron and is adapted to support considerable weight. Where the weight is less or where for other reasons it is desirable, the trolley may be run on ropes, rods, wires, or other suitable ways. The track may be suspended in any suitable manner, preferably by securing the ends to uprights. Figs. 1, 6, and 8 illustrate my preferred form of movable stop E, secured to the cable or track. This I construct in two semitubular pieces 30 and 31, adapted to embrace the rope or cable, the two pieces being fastened together about it by bolts or rivets at 32, 33, 34, and 35. This construction permits the stop to be turned over or swung about freely and to be coupled around the rope or cable from the sides. At any point on the stop, preferably near the end, is cut out the eye or arched opening 36, and to the portion of the cable thus exposed are bolted the clamps 37 and 38 by means of bolts 39 and 40. Each 60 clamp is curved or cut away about the rope B to afford a better grip around the rope. The insertion of these clamping members prevents longitudinal movement of the stop along the cable or rope. By removing these the 65 stop may be shifted to other points along the cable or track and secured by again affixing the clamp within the opening 36, or the two parts of the clamp and stop proper may be unbolted and taken off without changing the position of the rope or cable. The under portion of the stop E is provided with the flanged channel or guideway 41 for embracing the head 42 of the drop-bolt 29 on the trolley herein-after described and for gradually raising it 70 from one horizontal plane to another. This elevation is accomplished by providing the end of the guideway with the incline 43. It is also desirable to flare the ends of the guideway so that if the trolley should become 75 twisted out of the vertical the head 42 will

80

85

90

95

still be forced into the guideway and the trolley and stop brought into the same vertical plane. The stop or knocker and the carrier will operate upon ropes of different sizes. In 5 the smallest sizes the semitubular stop-sections 30 and 31 are held by the cross-bolts 32, 33, 34, and 35 in close contact, while with the large size ropes a space may be left between them.

10 C indicates the trip through which the hoisting-rope D is passed and which has the hook or coupling 22 depending from it for engaging and securing the load and the knob 23 projecting upward adapted to operate detents 20 and 21. While the drawings show two pulleys 18 and 19 on the frame A and the hoisting-rope D knotted to prevent its passing between the frame and the flanged pulley 18, thence passed beneath the flanged pulley 24 15 in the trip C, and over the flanged pulley 19, the load being supported by the hook 22 on trip C, it is obvious that any combination of ropes and pulleys which will raise and lower the load and cause the knob on the trip to operate the detents and any means for attaching the load to the trip may be used to advantage. Detents 20 and 21 are pivoted to turn about bolts 10 and 11, respectively. They are 20 so placed that when their lower portions are brought together the parts 25 and 26 form jaws which engage or bolt the knob 23 and support the load secured to trip C. On the upper or heel portion of each detent are the notches or click-surfaces 27 and 28, each adapted to embrace the block 44 of the drop-bolt 29. This drop-bolt consists of a shank having the 25 head 42 and the block 44 large enough when resting in notches 27 to hold the jaws 25 and 26 together. The bolt is also provided with vertical side guides 45, sliding in channels 46.

Having thus described my device, what I claim as new, and desire to secure by Letters Patent, is—

1. In combination, the track, a knocker, a 30 sleeve secured to the knocker and extending up over the track and forming a supplement-

tal track-section and a clamp on the track, said knocker having a head loosely engaging the clamp, substantially as described.

2. In combination, a knocker, a clamp on 50 the track comprising the two members secured together by bolts and a head on the knocker loosely engaging the clamp the said head being formed of open-work to permit access to the clamp, substantially as described.

3. In combination with a cable-track a 55 knocker comprising a plate extending below and laterally on each side of the track and means for securing the said knocker adapted to support the knocker on tracks of different sizes, substantially as described.

4. In combination a knocker comprising a plate extending below and laterally on each side of the track and suspending means therefor adapted to fit cable-tracks of different 60 sizes, substantially as described.

5. A knocker for hay-carrier or like tracks comprising a part having a catch or lug and having means for suspending it from the track and means on the knocker having jaws 70 reaching up alongside the track to engage a projection on the track to hold the knocker against movement longitudinally of the track, substantially as described.

6. A knocker for hay-carrier or like tracks 75 comprising a part having a catch or lug with a sleeve for suspending the said part from the track and means independent of the sleeve for engaging a projection on the track to hold the knocker against longitudinal displacement.

7. A knocker for hay-carriers or the like comprising a sleeve forming a supplemental track-section and a part suspended thereby and having a catch thereon and means at one 80 end only of the knocker to engage a projection on the track for holding the knocker against movement in both directions.

DAVID M. MOTHERWELL
